SAMUEL ROSENBERG, OF MILWAUKEE, WISCONSIN, ASSIGNOR TO RELIABLE KNITTING WORKS, OF MILWAUKEE, WISCONSIN, A CORPORATION OF WISCONSIN.

DESIGN FOR A COMBINED HEAD AND NECK COVERING.

58,944.

Specification for Design.

Patented Sept. 6, 1921.

Application filed February 2, 1920. Serial No. 355,760. Term of patent 3½ years.

To all whom it may concern:

Be it known that I, SAMUEL ROSENBERG, a citizen of the United States, residing at Milwaukee, in the county of Milwaukee and State of Wisconsin, have invented a new, original, and ornamental Design for a Combined Head and Neck Covering, of which the following is a specification, reference being had to the accompanying drawing, forming part thereof.

Fig. 2 is a view of the same as it appears in use.

I claim:

The ornamental design for a combined head and neck covering, as shown.

SAMUEL ROSENBERG.
